UNITED STATES PATENT OFFICE.

GEORGE W. LATHROP AND JAMES WILLIAM POWLES, OF RAMSEY COUNTY,
MINNESOTA.

SAFETY APPLIANCE FOR ELEVATORS.

1,023,857.

Specification of Letters Patent.

Patented Apr. 23, 1912

Application filed September 8, 1911. Serial No. 648,256.

To all whom it may concern:

Be it known that we, GEORGE W. LATHROP and JAMES WILLIAM POWLES, citizens of the United States, residing in Ramsey county, 5 in the State of Minnesota, have invented new and useful Improvements in Safety Appliances for Elevators, of which the following is a specification.

Our invention relates to improvements in 10 safety appliances for electrically driven elevators. Its object is to provide a device within quick and easy access of the elevator operator whereby the electric current may be cut off from the driving motors in case 15 the elevator controlling mechanism fails to operate.

A further object is to provide a device adapted to automatically cut off the current from the driving motors of an elevator, in 20 case the controlling mechanism permits the car to travel beyond a predetermined point either at the top or bottom of the elevator shaft.

A further object is to prevent or permit 25 as desired, the closing of the switch in the circuit of the driving motors after the car has been automatically stopped, at its limit of movement.

Our appliance is adapted for use in connection with the well known types of electric elevators in which the brakes are controlled by the electric current of the motor circuit. In these elevators the brakes are 30 inoperative when the circuit is connected to drive the car and are set to stop the car by discontinuing the current. With such elevators accidents have occurred by reason of defective or badly managed controllers which while continuing the current have 35 failed to regulate the movement of the car. In such event, the brake is useless because its application is dependent upon a cessation of current. Our purpose is to obviate the danger due to this cause by providing emergency means for throwing off the current.

In the drawings Figure 1 is a side elevation of our improved safety appliance, shown in use with an elevator of ordinary construction; Fig. 2 is a perspective view 40 in detail of the grip; Fig. 3 is a sectional

view taken on the line 3—3 of Fig. 2 and Fig. 4 is a detail view showing the connection between the cable and cord.

A car 9 of ordinary form and equipment is suspended by the cable 10 and connected 55 to driving mechanism (not shown) commonly used with electric elevators. A switch 11 which may be of the knife blade type, is mounted at the top of the elevator shaft and is arranged in the electric circuit 60 of the driving motors. The endless cable 12 is suspended vertically in the elevator shaft, extending over and guided by the idle sheaves 13 and 14. The cord 15 attached at one end to the handle of the switch 65 11, passes over the pulley 16 and is divided into two branches 17 and 18 which are respectively connected with the cable 12 on opposite sides of the sheave 13. It will thus be seen that the movement of the cable 12 70 in either direction will cause a downward pull on one or the other of the branches 17 and 18 of the cord 15 to open the switch 11.

We have provided a grip designed to be attached to the car and adapted to move the 75 cable 12 when manipulated by the operator. This grip comprises the members 21 and 22 pivoted together, the member 22 being mounted on a bracket 23 carried by the car. One end of the members form handles 24 80 and 25 while openings 26 and 27 through which the cable 12 passes, are formed in the blades 29 and 30. The stop pin 31 on the member 22 engages the member 21 and normally holds said members in position 85 against the action of the spring 32 which is fixed between the handles 24 and 25. When in normal position the openings 26 and 27 register with one another and permit the grip to pass freely over the cable 12. When 90 pressure is applied to the handles the blades 29 and 30 are forced apart thereby causing the opposed edges of the openings to pinch and hold the cable 12.

The bracket 23 may be rigidly attached 95 to the car, but we prefer to arrange it as follows: The guide 33 slotted at 34 is fixed to the car and forms a mounting for the bracket 23 which is clamped thereon in any position desired by the manipulation of the 100

thumb nut 35 on the bolt 36 extending through said slot 34 and bracket 23 and the sliding block 37.

The stops 38 and 39 are arranged on the cable 12 to impinge against the blades 29 and 30, when in normal position at predetermined points in the travel of the car, thus automatically breaking the motor circuit to stop the car, if permitted to pass 10 such points.

In operation, when the car becomes unmanageable the driver grasps the handles 24 and 25 and causes the grip to hold and move the cable 12. This action may take 15 place at any point in the travel of the car and regardless of the direction in which the car is passing will open the switch 11 thus stopping the motors and car. Damage to the switch 11 is prevented by the branches 20 17 and 18, which when in alinement limit the movement of the cable 12 and form a tie between the opposite sides of said cable as it is operated by the grip. The stop 38 at the top or the stop 39 at the bottom of the 25 elevator shaft is engaged by the grip if the car passes the predetermined upper or lower point, and breaks the circuit.

What we claim as new and desire to protect by Letters Patent is:

30 1. A device of the class described, comprising an electrically driven car, an endless cable supported in position adjacent to the car, a grip on the car having blades surrounding said cable and handles in the 35 car, a switch in circuit with a source of electric current, and a cord connecting said switch and cable, forming a stop for said cable to prevent damage to said switch and adapted to open the switch upon the movement of said cable in either direction.

2. A device of the class described, comprising an electrically driven car, an endless cable, guide pulleys for said cable, a grip vertically adjustable in the car in operative connection with said cable, stops on the cable in the path of said grip, a switch in circuit with a source of electric current, and connecting means between said switch and cable whereby said switch is opened by 45 the movement of said cable in either direction.

3. A device of the class described, comprising an electrically driven car, a movable endless cable supported in position adjacent to the car, a vertically adjustable grip in the car, stops on the cable in the path of said grip, a switch in circuit with a source of electric current and connecting means between said switch and cable where- 55 by said switch may be opened by the movement of said cable.

4. A device of the class described, comprising an electrically driven car, an endless cable supported in position adjacent to the car, a grip on the car in operative con-

nection with said cable, a switch in circuit with a source of electric current and connecting means between said switch and cable forming a stop for said cable to prevent destruction of said switch and adapted to open 70 the switch upon movement of the cable in either direction.

5. A device of the class described, comprising an electrically driven car, an endless cable, guide pulleys for said cable, a grip in 75 the elevator car in operative connection with said cable, a switch in circuit with a source of electric current, and a cord attached at one end to said switch for operating the same, and having two branches at its other end, said branches being connected to opposite sides of the cable whereby said cable is tied upon predetermined movement of said cable in either direction to prevent destruction 80 of the switch.

6. A device of the class described, comprising an electrically driven car, an endless cable, guide pulleys for said cable, a grip on the car in operative connection with said cable, a switch in circuit with a source of electric current and a cord attached at one end to said switch and having branches at its other end connected to opposite sides of said cable whereby said switch is opened by the 90 operation of the cable and said cable is tied by said branches to prevent destruction of the switch upon predetermined movement of the cable in either direction.

7. A device of the class described, comprising an electrically driven car, an endless cable, guide pulleys for said cable, a vertically adjustable grip on the car consisting of two pivotally connected arms having blades surrounding said cable and handles whereby said blades are operated, stops on 100 said cable in the path of the grip, a switch in circuit with a source of electric current and a cord connecting said switch and cable whereby the switch may be opened by the movement of the cable in either direction. 105

8. A device of the class described, comprising an electrically driven car, an endless cable, guide pulleys for said cable, a grip consisting of two arms having blades in operative connection with said cable and handles for moving said blades, a bracket for the grip, a guide on the car for said bracket, means for clamping the bracket on the guide, a switch in circuit with a source of electric current and connecting means between said switch and cable whereby said switch may be opened by the movement of said cable. 115

9. A device of the class described, comprising an electrically driven car, an endless cable, guide pulleys for said cable, a grip consisting of two arms having blades surrounding said cable and handles for operating said blades, a bracket for the grip, a slotted guide on the car for said bracket, a sliding block in the guide, a bolt in said 120 125 130

block and bracket, a nut on the bolt for
clamping said block and bracket to the guide,
stops on the cable in the path of said grip, a
switch in circuit with a source of electric
5 current and connecting means between said
switch and cable whereby said switch may
be opened by the movement of said cable.

In testimony whereof, we have signed our

names to this specification in the presence of
two subscribing witnesses.
